UNITED STATES PATENT OFFICE.

WORTHINGTON J. SNIDER, OF MADISON CITY, ASSIGNOR TO HENRY P. DEUSCHER, OF HAMILTON, OHIO.

DEVICE FOR IMPARTING AND ARRESTING MOTION.

SPECIFICATION forming part of Letters Patent No. 354,663, dated December 21, 1886.

Application filed September 13, 1886. Serial No. 213,451. (No model.)

To all whom it may concern:

Be it known that I, WORTHINGTON J. SNIDER, of Madison City, (post-office address Heno,) Butler county, Ohio, have invented certain new and useful Improvements in Devices for Imparting and Arresting Motion, of which the following is a specification.

This invention pertains to improvements in devices providing for the imparting and arrest of motion between two reciprocating parts of machinery.

The improvements will be readily understood from the following description, taken in connection with the accompanying drawing, which exhibits in perspective a device illustrating my invention.

In the drawing, A indicates a crank, which may for the present be assumed as in motion, so as to constitute a driver of the apparatus; B, a slide, to which, when desired, reciprocating motion is to be imparted; C, a guide for the slide; D, a connecting-rod reaching from the crank into engagement with the slide, the means of engagement being peculiar, as hereinafter set forth; E, an upwardly-opening notch in that end of the connecting-rod which engages the slide; F, a guide-slot formed in a projection from the upper surface of the slide, such guide-slot being parallel with the path of the slide movement, and being arranged to receive the end of the connecting-rod and permit under certain circumstances the reciprocation of the end of the connecting-rod therein; G, a lever pivoted to the slide and disposed transversely over the notched end of the connecting-rod, and adapted to drop into said notch and serve in locking the slide to the connecting-rod; H, a weight upon this lever, serving to insure the proper dropping of the lever into the notch; J, a lever pivoted to a fixed point, such point being shown as upon the guide C; K, a lifting-bar projecting from the lever J under the lever G, and parallel with the path of motion of the slide; and L, a projection from the upper surface of the slide to receive the slot F and to support the pivot of the lever G.

When the parts are in the position shown in the drawing and the crank is in motion, it is obvious that continuous reciprocating motion

will be transmitted to the slide, the lever engaging the notch of the connecting-rod serving to unite the connecting-rod to the slide. The fit of the lever in the notch and of the connecting-rod in the slot F is to be of such free character as to permit the proper flexation of the connecting-rod as its crank end rises and falls. If the lever J be pulled forward, the lifting-bar K will rise and the lever G will be lifted out of engagement with the connecting-rod. The connecting-rod will continue its motion, but the slide will remain stationary. In this condition, if the lever J be pushed backward, the lever G will again engage the notch and the slide will reciprocate. The lever J may extend as desired, and be provided with a handle; or it may be connected to cords or rods, by means of which it may be properly moved from a distance. The weight H is not essential, as the weight of the lever G may be sufficient to cause the proper engagement of the lever with the notch, and a spring may, if desired, be employed in connection with the lever to cause its engagement.

It is obvious that the slide may be the driver of the apparatus, reciprocating motion being in some manner imparted to it from without. In such case the crank becomes the driven element of the apparatus, the operation of the improvement being as in the previous case.

The connecting-rod D, instead of being connected with the crank, may be connected with a reciprocating piece of mechanism. The end of the connecting-rod which engages the slide is, so far as my improvements are concerned, a mere reciprocating element, and the function of my improvement is to provide for the impartation and arrest of motion between two reciprocating parts of machinery.

Numerous applications in the art of mechanism may be found for my device. Two illustrations will be given, intended to serve as mere examples. Let the slide B be connected with the plunger-rod of a pump or with devices for transmitting reciprocating motion from the slide to the plunger-rod, and let A represent a crank to serve in driving the pump through the medium of my improved device, rotary motion being imparted to the crank in any suitable manner. Then by means

of my device, while the crank is continuously revolving, the pump may be caused to operate or remain at rest, as desired. Again, let the slide be connected with a continuously-reciprocating part of a steam-engine or similar motor, and let A represent a crank to which rotary motion is to be at times imparted from such motor. Then by means of my device, while the slide B is continuously being reciprocated by the motor, the crank may be caused to revolve or remain at rest, as desired.

I claim as my invention—

In a device for imparting and arresting motion between two reciprocating parts of ma-

chinery, a slide, a connecting-rod provided with a notch, a guide formed upon the slide for the notched end of the connecting-rod, said guide being parallel with the path of motion of the slide, a lever pivoted to the slide and adapted to engage the notch of the connecting-rod, and a lever provided with a lifting-bar engaging said first-mentioned lever, combined and arranged to operate substantially as set forth.

WORTHINGTON J. SNIDER.
